ART OF CRACKING HYDROCARBONS

Filed June 29, 1929

UNITED STATES PATENT OFFICE

2,037,380

ART OF CRACKING HYDROCARBONS

Eugene C. Herthel, Chicago, Ill., assignor to Sinclair Refining Company, New York, N. Y., a corporation of Maine

Application June 29, 1929, Serial No. 374,859

2 Claims. (Cl. 196—58)

This invention relates to improvements in the cracking of higher boiling hydrocarbon oils such as gas oil to produce therefrom lower boiling hydrocarbon oils such as gasoline; more particularly the invention provides an improved operation for cracking higher boiling hydrocarbon oils such as gas oil in which residual tar or reduced residual tar discharged from a pressure distillation cracking operation is utilized to control the cracking operation and at the same time subjected itself to a further cracking operation and to an operation for the separation therefrom of a distillate fraction suitable to be supplied to the cracking operation.

According to this invention, a high boiling oil such as gas oil is forced through a heating zone under superatmospheric pressure and thence into an expansion chamber, this oil is heated to a relatively high cracking temperature in the heating zone, a residual tar from a pressure distillation cracking operation is introduced into the oil passing from the heating zone to the expansion chamber reducing the temperature of the hot oil discharged from the heating zone prior to separation of vapors from the oil mixture in the expansion chamber, the pressure on the oil passing from the heating zone to the expansion chamber is reduced before it enters the expansion chamber but either before or after the introduction of the residual tar, vapors including vapors of the desired lower boiling hydrocarbon oils and vapors separated from the introduced residual tar are taken off from the expansion chamber and residue is discharged from the expansion chamber. The vapors taken off from the expansion chamber are, with advantage, subjected to a refluxing operation from which reflux condensate including condensed components separated from the introduced residual tar in the expansion chamber is returned to the heating operation.

The invention will be further described in connection with the accompanying drawing which illustrates one form of apparatus adapted for carrying out the invention. It will be understood that the accompanying drawing is largely diagrammatic and conventional; the apparatus is shown generally in elevation, partly in section and with parts broken away.

The invention is generally useful in conjunction with pressure distillation cracking operations. The pressure still system illustrated is of the general type described in Letters Patent No. 1,285,200, issued to Sinclair Refining Company, November 19, 1918, on the application of Edward W. Isom. In the operation of the system illustrated, a charge of oil is circulated from the bulk supply drum 50 upwardly through the heating tubes 51 arranged in the heating furnace 52 and back to the bulk supply drum 50 by means of

pump 53, vapors are taken off from the bulk supply drum under superatmospheric pressure and subjected to a refluxing operation in the reflux tower 54 from which reflux condensate is returned to the circulating charge, and vapors remaining uncondensed escape from the reflux tower 54 to the condenser 55 arranged to discharge into receiver 56 from which the condensed cracked distillate product is discharged through connection 57 and uncondensed vapors and gases through connection 58, pressure in the system being maintained and regulated by means of valve 59 or by means of appropriate valves arranged beyond the condenser or receiver. Residual tar is discharged from the bulk supply drum 50 during operation through connection 60. The operation of the system may be carried out, for example, as described in Letters Patent No. 1,598,136, issued to Sinclair Refining Company, August 31, 1926, on my application. The pressure still system illustrated may be, and usually is, one of a battery of several such systems; manifold connections to such a battery are indicated at 61 and 62. As further examples, the invention is also useful in conjunction with pressure still systems operated as described in my application filed January 12, 1928, Serial No. 246,262, or in conjunction with pressure still systems in which a single pass heater discharges into a vaporizing zone from which vapors are taken off under superatmospheric pressure and from which residual tar is discharged.

In the pressure still system illustrated, the operation of the reflux tower 54 is controlled by the regulated introduction of stock to be cracked through connection 63, or this control may be supplemented by the regulated introduction of a part of the distillate product or some similar fraction through connection 64, or the operation is controlled by the regulated introduction of part of the distillate product or some similar fraction through connection 64.

The cracking operation of the present invention is carried out, in the apparatus illustrated, in the heating coils 9, 10 and 11, expansion chamber 12 and fractionating tower 16. The heating furnace in which the heating coils 9, 10, and 11 are arranged comprises a series of heating flues, a firebox and a stack flue connected so that the heating gases from the firebox pass successively through the heating flues 2, 3 and 4 to the stack flue 5. Ducts, including suitable forcing means, are provided to permit recirculation of a part of the heating gases escaping from flue 3 to flue 4 through flues 2 and 3 as shown at 6 and to permit recirculation of a part of the heating gases escaping through the stack flue 5 through flues 3 and 4 as shown at 7. The heating coils 9, 10 and 11 comprise banks of heating tubes connected to

form three single continuous coils. A high boiling oil such as gas oil is forced by means of pump 8 through preheating coil 9, cracking coil 10 and cracking coil 11 in succession and then into expansion chamber 12 through pressure regulating and reducing valve 13. Residue such as fuel oil is discharged from expansion chamber 12 through connection 14. Vapors are discharged from expansion chamber 12 through connection 15 into the lower end of fractionating tower 16. This fractionating tower may be of any conventional type, a "bubble" tower, for example. The fractionating tower 16 and the expansion chamber 12 are with advantage thoroughly lagged or thermally insulated. In the fractionating tower 16 those components of the vapor mixture heavier than suitable as components of the desired product are condensed. The operation of this tower may be controlled by the regulated introduction of stock to be cracked through connection 17, or this control may be supplemented by the regulated introduction of a part of the distillate product or some similar fraction through connection 18, or the operation may be controlled by regulated introduction of a part of the distillate product or some similar fraction through connection 18. Vapors remaining uncondensed escape from the upper end of tower 16 through connection 20 to condenser 21 arranged to discharge into receiver 22 from which the condensed cracked distillate product is discharged through connection 23 and uncondensed vapors and gases through connection 25.

In carrying out the present invention, the high boiling oil or oil mixture supplied thereto is heated to a relatively high cracking temperature in the cracking coils 10 and 11 and as this hot oil passes from the cracking coil 11 to the expansion chamber 12 through connection 87 residual tar or reduced residual tar discharged from the pressure distillation cracking operation through connection 60 is introduced through connections 31 and 88 by means of pump 32 reducing the temperature of the hot oil discharged from the cracking coil 11 prior to separation of vapors from the resulting oil mixture in the expansion chamber 12. The pressure regulating and reducing valve 13 is shown positioned to reduce the pressure on the hot oil discharged from the cracking coil 11 prior to the introduction of the residual tar through connection 88. This is usually the more advantageous arrangement, although this pressure regulating and reducing valve may be positioned beyond the junction of connections 87 and 88.

The high boiling oil supplied to the cracking coil 10 may comprise raw gas oil supplied through connections 26, 27 and 19 by means of pump 24, or reflux condensate supplied from the lower part of fractionating tower 16 through connections 28, 29 and 19 by means of pump 8, or reflux condensate supplied from an intermediate part of fractionating tower 16 through connections 30, 33, 29 and 19 by means of pump 34, either of which reflux condensates may include components of raw oil introduced as a refluxing medium into the fractionating tower 16, or mixtures of such reflux condensates and raw oil supplied through connection 26, for example.

The residual tar from the pressure distillation cracking operation may be introduced into the hot oil passing from the heating zone to the expansion chamber, through connections 31 and 88 in the apparatus illustrated, as discharged from the pressure distillation cracking operation, or oil components of this tar may be evaporated

therefrom, as described in Letters Patent No. 1,677,773, issued to Sinclair Refining Company, July 17, 1928, on the application of Thomas de Colon Tiff and myself, for example. In the apparatus illustrated, the residual tar from the pressure still system may be discharged directly through connections 60, 35 and 36 to pump 32, supplying this residual tar through connection 31 to the cracking operation of this invention, or residual tar from the pressure still system may be discharged through connections 60 and 37 into an evaporator 38 in which a pressure lower than that prevailing in the pressure still system is maintained and in which part of the residual tar is vaporized to escape as vapor through connection 39 to tower 40, the remaining reduced residual tar being discharged through connections 41 and 36 to pump 32. All or part of this residual tar may, in some cases, be passed through cooler 91. The vapors entering tower 40 through connection 39 may be condensed or may be separated into higher and lower boiling fractions therein. Condensate is discharged from tower 40 through connection 42. Uncondensed vapors escape therefrom through connection 43 to condenser 44 arranged to discharge into receiver 45 from which condensate is discharged through connection 46 and uncondensed vapors and gases through connection 47. Pressure in the evaporator 38, or in the evaporator 38 and the tower 40, may be maintained and regulated by means of valve 48 or valve 49 or by means of appropriate valves arranged beyond the condenser or receiver. The operation of tower 40 is controlled by the regulated introduction of stock to be cracked through connection 65, or this control may be supplemented by the regulated introduction of a part of the distillate product or some similar fraction through connection 66, or the operation may be controlled by the regulated introduction of a part of the distillate product or some similar fraction through connection 66. In carrying out this invention, the operation of the evaporator 38 may be controlled by regulated introduction of a cooling medium, such as gas oil or reduced crude oil, through connection 89, for example, to avoid too high concentration of pitch constituents in the residual tar discharged through connection 41. To increase the concentration of pitch constituents, steam may be supplied through connection 90.

Pumps 67 and 68 are provided for supplying part of any one or more of the several distillate products collected in the receivers 22, 56 and 45 to any one or more of the towers 16, 40 and 54 as refluxing media through connections 69, 70, 71 and 72 or such of these connections as may be required.

The total condensate separated in tower 16 may be supplied to the cracking coils 10 and 11, or a higher boiling condensate and a lower boiling condensate may be separated in this tower and the lower boiling condensate supplied to the cracking coils 10 and 11 and the higher boiling condensate supplied to the pressure distillation cracking operation, connections 74 and 75 being provided for this purpose. Condensate separated in tower 40 may be supplied, or in part supplied, to cracking coils 10 and 11 through connections 42, 76, 29 and 19 by means of pump 77 or may be supplied or in part supplied to the pressure distillation cracking operation through connections 42, 78 and 75 by means of pump 77. A single raw stock, gas oil for example, may be supplied or in part supplied to tower 16 as a 75

refluxing medium through connections 26, 79 and 17, or supplied or in part supplied to tower 40 as a refluxing medium through connections 26, 79, 80 and 65, or supplied or in part supplied to 5 tower 54 as a refluxing medium through connections 26, 79, 80 and 63. Or, a lower boiling raw stock may be supplied or in part supplied to tower 16 as a refluxing medium through connections 26, 79 and 17 and a higher boiling raw 10 stock supplied or in part supplied to tower 40 or to tower 54 as a refluxing medium through connections 81, 82 and 80 and either or both of connections 63 and 65 by means of pump 83. Where a lower boiling raw stock is so supplied 15 to tower 16, the total higher boiling raw stock may be supplied to tower 40 through connections 81, 82, 80 and 65 and the total condensate mixture from tower 40 supplied to tower 54, that is to the pressure still system, through connections 20 42, 78, 75 and 63.

If excess heat is available in the expansion chamber 12, a crude stock, for example, a crude oil or a reduced crude oil, may be supplied together with the residual tar from the pressure 25 distillation cracking operation through connection 88, the crude stock being supplied through connections 84 and 85 by means of pump 86. Such crude stock may thus be utilized to supplement control of the cracking operation by introduction of the residual tar and at the same time 30 may be separated, in the expansion chamber 12, into a vaporized fraction escaping to the fractionating tower 16 and a residual stock mixing with the residue collecting in and discharged 35 from the expansion chamber. Raw stocks, of gas oil character for example, may be so separated from such crude stocks and supplied to the cracking operation of the invention or to the associated pressure distillation cracking operations 40 as condensates from fractionating tower 16, for example.

In carrying out the invention in the apparatus illustrated, the discharge pressure from the cracking coils 10 and 11 may be in the neighborhood of 400-800 pounds per square inch and the pressure in the expansion chamber 12 may approximate atmospheric pressure, or the expansion chamber 12 may be operated under superatmospheric pressures, for example, 20-25 pounds 45 per square inch, lower however than the discharge pressure from the cracking coils. Fractionating tower 16 may be operated under substantially the same pressure as the expansion chamber 12, or when the expansion chamber 12 is operated under superatmospheric pressure the fractionating tower 16 may be operated under a pressure lower than that prevailing in the expansion chamber 12. Raw oil supplied through connection 19 may enter the preheating coil 9 50 at a temperature approximating 60-80° F. or, where condensates are supplied hot from either or both of the towers 16 or 40, the oil supplied through connection 19 may be at a temperature as high as 300° F. or higher. Oil passing from 55 the preheating coil 9 to the cracking coil 10 may be at a temperature approximating 550-750° F. and the oil may be heated in the cracking coils 10 and 11 to a temperature, as discharged, approximating 900-1000° F. Residual tar introduced 60 into the hot oil passing from the cracking coils 10 and 11 to the expansion chamber 12 may be

supplied through connection 88 at a temperature in the range of 350-650° F., or at a lower temperature where this residual tar is admixed in connection 88 with a raw crude stock supplied through connection 85. The resulting oil mixture 5 may be discharged into the expansion chamber 12 at a temperature approximating 700-900° F. when the fractionating tower 16 is operated under substantially atmospheric pressure, the temperature of the escaping vapors may be in the neighborhood of 300-600° F. It will be understood 10 that the foregoing temperatures and pressures are given to assist in the illustration of the invention and that the invention is not limited thereto. The precise conditions of operation of 15 the pressure still system or systems from which residual tar is supplied to the cracking operation of this invention are not given because they are not essential with respect to the present invention, varying widely with the different types 20 of pressure distillation cracking operations.

I claim:

1. In cracking higher boiling hydrocarbon oils to produce lower boiling hydrocarbon oils, the improvement which comprises forcing high boiling oil through a heating zone under superatmospheric pressure and thence directly into an expansion chamber, heating the oil to a cracking temperature in the heating zone, introducing a concentrated residual tar from a pressure 25 distillation cracking operation into the oil passing from the heating zone to the expansion chamber and thereby reducing the temperature of the hot oil discharged from the heating zone prior to separation of vapors from the oil mixture, 30 reducing the pressure on the oil passing from the heating zone to the expansion chamber, taking off vapors including vapors of the desired lower boiling hydrocarbon oils and vapors separated from the introduced residual tar from the expansion 35 chamber and discharging residue from the expansion chamber.

2. In cracking higher boiling hydrocarbon oils to produce lower boiling hydrocarbon oils, the improvement which comprises forcing high boiling oil through a heating zone under superatmospheric pressure and thence directly into an expansion chamber, heating the oil to a cracking 45 temperature in the heating zone, introducing a concentrated residual tar from a pressure distillation cracking operation into the oil passing from the heating zone to the expansion chamber and thereby reducing the temperature of the hot oil discharged from the heating zone prior to separation of vapors from the oil mixture, reducing 50 the pressure on the oil passing from the heating zone to the expansion chamber, taking off vapors including vapors of the desired lower boiling hydrocarbon oils and vapors separated from the introduced residual tar from the expansion 55 chamber and subjecting them to a refluxing operation, supplying reflux condensate including condensed components separated from the introduced residual tar in the expansion chamber from the refluxing operation to the heating operation, taking off vapors including vapors of the desired lower boiling hydrocarbon oils from the refluxing operation and discharging residue from the expansion chamber.
